UNITED STATES PATENT OFFICE.

EDWARD T. CONDON, JR., OF NEW YORK, N. Y.

AUTOMATIC STOP MECHANISM FOR TALKING-MACHINES.

1,334,350.

Specification of Letters Patent. Patented Mar. 23, 1920.

Application filed August 11, 1916. Serial No. 114,342.

To all whom it may concern:

Be it known that I, EDWARD T. CONDON, Jr., a citizen of the United States, and a resident of New York, in the county of New York and State of New York, have invented certain new and useful Improvements in Automatic Stop Mechanism for Talking-Machines, of which the following is a specification.

The invention relates to improvements in talking machines, more particularly to mechanism for automatically effecting the stopping of the record table at the completion of a selection; and it has for its object to provide a device of this character which shall be simple in construction, inexpensive to manufacture, positive and direct in its action and readily attachable to existing machines.

The nature of the invention will be best understood when described in connection with the accompanying drawings, in which—

Figure 1 is a plan of a talking machine with stop mechanism attached.

Figs. 2 to 4 are detail views, in plan, of the stop mechanism, illustrating the same in various stages of its action.

Fig. 5 is a detail front elevation of the stop mechanism.

Fig. 6 is a detail end view, partly in section, illustrating the stem mounting of the stop mechanism.

Similar characters of reference designate corresponding parts throughout the several views.

Referring to the drawings, 10 designates a suitable box or cabinet containing the usual mechanism for effecting rotation of a record table 11 designed to support and rotate a disk record 12. The tone arm 13, sound box 14 and stylus 15 may be of the usual construction and form no part of the present invention, which relates more particularly to mechanism designed to automatically engage the circumference of the table 11 to bring the same to a full stop at the completion of a selection. To this end, there is provided a suitable supporting means such as a plate or bracket 20 designed to be secured to the top of the casing 10 in the proper position for the purpose intended. The said bracket is provided with two upwardly-extending ears forming an inner bearing 21 and an outer bearing 22, the latter being provided with an outwardly-ex-

tending flange portion 23. In the two bearing members 21 and 22 is mounted, to be radially reciprocable with respect to the table 11, a brake member or rod 24 provided at its inner end with a suitable friction piece or shoe 25 which is adapted to make contact with the circumference or rim of the said table 11 to bring the latter to a full stop. The said rod 24 is urged inwardly toward the rim of table 11 by means of a spring 26 coiled about said rod and located between the bearing 22 and a shoulder 27 of said rod, its innermost position and position for effecting the stopping of the table's rotation, being indicated in Figs. 4 and 5. At its outer end, there is mounted in the rod, as will hereinafter be more fully set forth, a stem 28 extending upwardly through the flange 23, and when the stop is in locking position through a socket 29 thereof, whose vertical axis lies in a plane with the longitudinal axis of the said rod. The stem, when in socket 29, maintains a substantially upright position and is provided at its outer end with an arm 32 turned first substantially perpendicular to the longitudinal axis of rod 24, then parallel thereto with an upward inclination and in a direction toward the table 11, and thereupon with a further upward bend perpendicular to the longitudinal axis of said rod toward the tone arm 13, which it is designed to engage.

An outlet slot 30 is provided from the socket 29 terminating at the tone arm side in a nose 31, formed at the outer end thereof and of sufficient bearing surface or shoulder to accommodate the angular motion of stem 28, as will be hereinafter set forth, said nose having its releasing edge substantially in the plane of the slot and rod axes, or preferably slightly displaced therefrom in the direction of the tone arm. The stem 28 is mounted in the outer end of rod 24 in such a manner as to maintain a friction fit therein, permitting the said stem, under certain conditions, to move relatively with respect to the said rod, turning therein, as well as to effect angular movement of the rod itself. This may be accomplished, for example, by providing stem 28 with an upper shoulder 33 against which is forced a block 34. The portion of the stem below same is placed through a vertical hole 35 of the rod 24, a spring washer 36 being interposed as well as a locking washer 37, the latter bearing against a lower shoulder 38 of

the projecting end of the stem which is upset to the required extent to afford the desired degree of friction, and is shown more particularly in Fig. 6.

5 To operate the stop, it is necessary first to move inwardly the tone arm to a position corresponding to the last groove, or end of the selection, of the record to be engaged by the stylus 15, the stem 28 remaining in the 10 socket 29 during this stage of the setting. During this stage, the arm 32 is rotated until its free end contacts with the tone arm 13. The tone arm is then returned to the proper starting position, as shown in Fig. 1, and the 15 stem 28 grasped, near its connection with the rod, to avoid relative movement between said stem and its rod 24, and drawn out of the notch or socket 29 through the slot 30 and locked against the shoulder 31, the arm 20 32 moving toward the tone arm 13, a distance determined by the design of the shoulder. Withdrawing the stem 28 from its socket, releases the brake member from the 25 table 11, which begins its rotation to effect the reproduction of the record. Eventually, and before the completion of the record, engagement of the tone arm 13 with arm 32 is effected, the stem 28 then being gradually angularly rotated back to its original 30 set position into the plane of the axes of rod 24 and socket 29. Thereupon, the said stem 28 is moved past the nose or shoulder 31 and suddenly released to shoot the rod 24 inwardly under the influence of its coiled 35 spring 26, returning through slot 30 to its locking or braking position in the socket 29 and effecting the stopping of rotation of table 11. Should it be desired to operate the machine without the automatic stop, the 40 stem 28 may be held in inoperative position, for example, by forcing it into an auxiliary socket 40 located upon the opposite side of the said slot 30.

I claim:

45 1. Stop mechanism for talking machines, comprising: a reciprocably and rotatably mounted brake member, a setting member frictionally pivoted to the brake member; to effect an angular movement thereof and to allow of an oscillation thereon about the pivoted axis for purpose of adjustment relatively to the tone arm of the talking machine with which said member is adapted to engage; and means to hold said brake member in retracted position.

2. Stop mechanism for talking machines, comprising: a reciprocably and rotatably mounted rod provided with a brake piece at one end; a spring coiled about said rod 50 to urge the same toward the turn-table of said machine; a stem frictionally pivoted to the other end of said rod to effect an angular movement thereof and to allow of an oscillation thereon about the pivoted axis 55 for purpose of adjustment relatively to the

tone arm of the talking machine with which said stem is adapted to engage; and means to hold said rod in retracted position.

3. Stop mechanism for talking machines, comprising: a reciprocably and rotatably mounted rod provided with a brake piece at one end; a spring coiled about said rod to urge the same toward the turn-table of 70 said machine, a stem frictionally pivoted to the other end of said rod to effect an angular movement thereof and to allow of an oscillation thereon about the pivoted axis 75 for purpose of adjustment relatively to the tone arm of the talking machine with which said stem is adapted to engage; and means to hold said rod in retracted position, including a plate provided with a socket to receive the stem, with an exit slot therefrom and a shoulder or nose at the outer end of 80 said slot.

4. Stop mechanism for talking machines, comprising: a reciprocably and rotatably mounted rod provided with a brake piece at one end, and at the other end with a hole 90 extending entirely therethrough; a stem fitting therein, the rod being upset at the projecting end, and provided with a shoulder at the entrance portion, suitable washers included between said upset end and the rod and the shoulder and rod to frictionally 95 pivot the stem to the rod and to effect an angular movement thereof and to allow of an oscillation thereon about the pivoted axis for purpose of adjustment relatively to the tone arm of the talking machine with which 100 said stem is adapted to engage; and means to hold said rod in retracted position.

5. Stop mechanism for talking machines, comprising: a reciprocably mounted brake member; a setting member connected therewith to effect angular movement of same and adapted for engagement with the tone arm of the talking machine, said two members being relatively movable with respect to each other; means to temporarily hold said 110 brake member in retracted and set position; and means to permanently retain said brake member in inoperative and non-set position.

6. Stop mechanism for talking machines, comprising: a reciprocably mounted brake 115 member; a setting member connected therewith to effect angular movement of same and adapted for engagement with the tone arm of the talking machine, said two members being relatively movable with respect 120 to each other; and a plate provided with a socket to receive the setting member in set position, with an exit slot therefrom and a shoulder or nose at the outer end of said slot, and with a further socket to retain the 125 setting member in inoperative position.

7. Stop mechanism for talking machines, comprising: a reciprocably and rotatably mounted brake member; a setting member pivoted thereto to effect an angular move- 130

ment of same and adapted for engagement with the tone arm of the talking machine, said two members being relatively movable with respect to each other; and means provided with a socket to receive the setting member in set position, with an exit slot therefrom and a shoulder or nose at the outer end of said slot, and with a further socket located beyond the first-named socket 10 to retain the setting member in inoperative position.

8. Stop mechanism for talking machines, comprising: a bracket member adapted to be secured to the talking machine and having two upturned ears forming bearings; a spring urged rod mounted therein and provided at its inner end with a brake piece; a stem frictionally secured to the other end of the rod, perpendicularly thereto and having an extending arm adapted to engage the tone arm of the talking machine, and one of said ears having a plate extending at right angles thereto, provided with a socket to receive the said stem, with an exit slot therefrom and a shoulder or nose at the outer end of said slot.

9. Stop mechanism for talking machines, comprising: a bracket member adapted to

be secured to the talking machine and having two upturned ears forming bearings; a rod mounted to reciprocate and rotate in said bearings, provided at its inner end with a brake piece; a spring coiled about said rod between a shoulder thereof and an ear of said bracket member to urge the rod in the direction of the turn-table of said talking machine; a stem passing entirely through a hole at the other end of said rod, upset at the protruding end and provided with a shoulder at the entrance portion, and suitable washers included between said upset end and the rod and the shoulder and the rod to frictionally pivot the stem to the rod to effect an angular movement of the latter and allow of an oscillation thereon about the pivoted axis for purpose of adjustment relatively to the tone arm of the talking machine; and a plate extending from one of said ears, provided with a socket to receive the said stem, with an exit slot therefrom and with a shoulder or nose at the outer end of said slot.

Signed at New York, in the county of New York and State of New York this 10th day of August, A. D. 1916.

EDWARD T. CONDON, JR.
